SPEED CUP BALANCING MACHINE

Charles W. McKinley, Lucian B. Smith, and Clarence B. Dinsmore, Flint, Mich., assignors to General Motors Corporation, Detroit, Mich., a corporation of Delaware

Original application November 1, 1935, Serial No. 47,750. Divided and this application February 24, 1938, Serial No. 192,302

5 Claims. (Cl. 308—2)

This application relates to a speed cup balancing machine. It is a division from our application Serial No. 47,750 filed November 1, 1935.

The object of the invention is the provision of 5 a novel form of oscillating bearing to reduce friction at the bearing support, a bearing which is useful in the speed cup balancing machine of the above-mentioned application and in many other relations. 10 Other objects and advantages will be understood from the following description. Only so much of our balancing machine of our prior application is shown and described as is needed to indicate the relation to it of the oscillating bearing 15 of the present divisional application.

In the drawing:

Figure 1 is a plan view of the balancing machine.

Figure 2 is a perspective of parts thereof constituting the oscillating bearing for the spindle of the speed cup which is to be balanced.

Referring to the drawing, a base 11 is shown on platform 10. Secured to the base 11 at 13 are strips 15 slidable relative to which is a motor 19. 25 Associated with the fixed abutment 21 is a lever 23 pivoted at 26 to the abutment 21 and a link 25 pivotally connected at 28 to the lever and at 30 to the motor. Springs 27 are positioned between the abutment 21 and the motor. When the lever 23 is raised so that pivot 28 is above the line joining pivots 26 and 30, the springs 27 assist the lever and link in reciprocating the motor away from the abutment. A suitable cutter, not shown, is operable by the motor to cut material 30 from the outer bottom wall of the speed cup as will be explained. The drawing shows a bar 29 fixedly mounted upon the base. It has vertical end walls 31 to which are secured by fastening means 33 flat plates of resilient steel 35 and 35'. These plates are free to vibrate toward and from each other. The plates extend to the region of a die 37 which projects within and seats against the inner side of the bottom wall of the base of 45 the speed cup. To the ends of plates 35 and 35' are secured by fastening means 39 spool supports 40, the spool supports having opposed lugs 41 carrying pins 43, the adjacent ends of which are tapered for the rotary support of spools 44. The 50 parts are positioned and dimensioned so that when the speed cup spindle 45 is supported as shown the cup 47 is in contact with the die 37 as explained above. Secured to the cross bar 29 is a synchronous motor 51 having a shaft 53, the latter being provided with a plural face cam 55

engaging abutments 57 secured to the resilient plates.

In the operation of the machine the speed cup is mounted as described. The vibrating movements of the resilient plates 35 and 35' insure that any out of balance condition of the speed cup causes it to rotate about the spools until the unbalancing mass is in the lower end of the vertical axis. As explained in the parent case, lever 61 is then rotated to punch a hole in the bottom 10 wall of the cup. The lever is then withdrawn and the speed cup swings to a new position of rest. This new position again brings the unbalancing weight into the lower part of the vertical diameter of the cup, the vibrating spools 15 being relied on to insure the free swinging of the cup. The process is then continued by swinging lever 23 so that springs 27 may move the motor together with a head 63 carried thereby and adapted to move jointly therewith and grip the 20 base of the speed cup between itself and the die 37. The rotation of lever 23 also introduces an electric circuit, not shown, operable to actuate motor 19. The cutter driven by the motor then cuts material from the outer bottom wall of the 25 cup in quantity sufficient to balance the cup. The depth of the cutting is determined by the arc of rotation of the speed cup and is measured by the rotation of an arm 65 carrying a pin 67. The arm 65 is rotated until its pin registers with 30 the hole which has been punched by the action of lever 61. Suitable mechanism associated with lever 65 and with the cutting means of the motor, this mechanism not being shown, determines the depth of the cutting and insures the correct 35 balancing of the cup.

In the parent application are claims for the machine for balancing the cup. The present divisional application aims to afford protection on the oscillating supporting means best shown in 40 Figure 2, this supporting means being useful with the balancing machine and in other relations.

We claim:

1. Means to support an element for free rotation, said element having a spindle, said support 45 comprising members upon which said spindle rests, and means to move said members simultaneously toward and from each other to reduce to a minimum the friction at the points of support and to prevent axial movement of said element.

2. The invention defined by claim 1, said spindle resting on said members on opposite sides of said element.

3. The invention defined by claim 1, said means 55

comprising flexible arms carrying said members and a power driven multi-faced cam between and operable on said arms.

4. An oscillating bearing comprising substantially parallel arms, a support carried at one end of each arm, a spool carried by each support upon which spools the ends of a supported element may rest, said arms being flexible and means whereby

said arms may be simultaneously moved toward and from each other.

5. The invention defined by claim 4, together with rotatable cam means between and operable jointly upon said arms. 5
